UNITED STATES PATENT OFFICE.

JAMES W. ANDERSON, OF NEW YORK, N. Y., ASSIGNOR TO F. N. BURT COMPANY, LIMITED, OF BUFFALO, NEW YORK, A CORPORATION OF ONTARIO, CANADA.

LABELING-MACHINE.

1,130,129.

Specification of Letters Patent.

Patented Mar. 2, 1915.

Application filed August 2, 1913. Serial No. 782,694.

To all whom it may concern:

Be it known that I, JAMES W. ANDERSON, a citizen of the United States, residing at New York, in the county of New York and State of New York, have invented certain new and useful Improvements in Labeling Machines, of which the following is a full, clear, and exact description, such as will enable others skilled in the art to which it applies to make and use the same.

This invention relates to machines for attaching labels to articles, and with respect to its more specific features, to mechanism for automatically attaching a plurality of labels to boxes.

One of the objects of the invention is the provision of a practical machine of the class described wherewith labels may be separately applied to the inside and the outside of relatively small boxes, as, for example, cigarette boxes.

Another object of the invention is the provision of a machine of simple construction and efficient operation, capable of automatically labeling boxes as described.

Another object of the invention is the provision of a mechanism of the character referred to wherewith labels may be automatically applied to the inside of a plurality of boxes in an accurate and efficient manner.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, showing one of the possible embodiments of the invention, Figure 1 is a side elevation of the labeling machine; Fig. 2 represents a plan view of the machine; Fig. 3 represents a longitudinal horizontal section throughout an intermediate portion of the machine and showing more especially the relationship of the various operating elements; Fig. 4 is a side elevation, partly in section, of one of the box carriers and its operating mechanism; Fig. 5 is a plan view of the construction illustrated in Fig. 4, partly broken away, showing the parts more clearly; Fig. 6 is an elevation of the device employed to

press labels against the inside of the boxes; Fig. 7 is a side elevation showing cam and operation connections for the glue pad and label holder of the inside labeling device; Fig. 8 is an elevation of the mechanism for feeding one of the boxes to the rotary carrier; Fig. 9 is an end plan view of the endless belt comprising a portion of the feeding mechanism shown in Fig. 8; Fig. 10 is a detail rear view of the picker finger; Fig. 11 is a side elevation, partly in section, showing the detailed construction of one of the carriers for the inside labeling of boxes associated with a glue pad which transfers glue to the inside of the box; Fig. 12 is a front view of the part shown in Fig. 11; Figs. 13, 14 and 15 are detail views of different parts; Fig. 16 is a side elevation of the label mechanism from which labels are supplied to the inside of the boxes; Fig. 17 is a plan view of the label mechanism shown in Fig. 16; and Fig. 18 is a detail view showing the construction of the device for stripping the boxes from the machine.

In labeling articles, and especially in labeling relatively small boxes such as those employed as a container for cigarettes, it is especially desirable that the labels shall be applied to the boxes in correct position; that they shall be smoothly and evenly applied, free from air bubbles, etc.; that the adhesive employed to attach the labels to the boxes shall be kept at the place or places where it performs its function and not be deposited on the surface of the box in such a manner as to render the box unsightly. Taking these and other requirements into consideration, the machine herein described automatically labels boxes in accordance with the requirements above stated and others.

Referring now more particularly to the drawings, the supporting frame of the machine comprises an upper table 1 and a lower table 2, preferably slightly elevated on legs 3. A main driving shaft 4 is horizontally journaled in bearing standards 5 on the lower table, and is driven by a belt pulley 6 rotatably mounted on the outer end of the main shaft and adapted to be coupled therewith by a clutch 7 operated by any suitable means. The main shaft 4 terminates adjacent the central longitudinal line of the lower table and is there provided with a bevel gear 8, meshing with a similar gear 9

on a longitudinal horizontal countershaft 10, supported in standard bearings 11 on said table. A second longitudinal shaft 12, supported in standard bearings 13 on the lower table is driven from said shaft 11, through bevel gears 14, 15 and 16, the gear 15 being fast on a vertical shaft journaled in bearing sockets 17 on the lower and the upper table. In line with the main shaft is a third countershaft 18, supported in bearing standards 19 on the lower table, and driven from the bevel gear 9 by a companion bevel gear 20. A second vertical shaft 21, at one end of the frame is driven from the shaft 12 by bevel gears 22 and 23.

The numeral 24 represents an endless belt box conveyer, the upper ply of which is adapted to support boxes open side down and to move them successively into a predetermined position wherein they are fed one by one to a carrying device which conveys them into positions where labeling operations are performed thereon, as will be hereinafter explained. Preferably the endless belt box supply device is of the construction disclosed in Patent No. 1,019,351, dated March 5, 1912, although it may be of any form capable of accomplishing the desired results. The belt 24 is driven through a sprocket wheel 25 on one of the belt pulley shafts, chain 26, and a sprocket wheel 27 on the shaft 18.

The upper table has a large vertical bearing sleeve 28, providing a horizontal bearing surface 29, and a hollow rotary shaft 30 is journaled in the sleeve 28, and has a circular flange 31 supported by the surface 29 through an intermediate hardened bearing ring 32, as illustrated. Bolted to the upper face of the shaft 30 is a plate 33 on which are provided or supported a plurality of carriers adapted to receive and position the boxes supplied from the belt 24. The hollow shaft 30 extends through the upper table and an element 34 of a Geneva gear is secured thereto, said element being rotated step by step by a wheel 35, having a pin 36 adapted to engage the slots 37 of the wheel 34, the wheel 35 being constructed to peripherally engage circular recesses 38 in the wheel 34, and lock said wheel 34 between the intervals of its movement. The wheel 35 is fast on the vertical shaft 39 to which the gear 15 is attached, and is designed to make a complete revolution for each step movement of the carrier.

The carriers on the plate 33 are designed to support boxes so as to expose the interior thereof, and preferably so support the boxes that the interior thereof is presented downwardly. The carriers are concentrically disposed relative to the axis of the shaft 30, being adapted to move in endless horizontal paths, and as these carriers are identical in construction a description of one will answer

for all. In the present embodiment, each carrier comprises a support or pair of tracks 40 connected to the plate 33, and extending generally radially thereof. The tracks 40 are formed by the ends of plates 41, pivoted to generally radially disposed box-inclosing walls 42 and 43 spaced apart and extending downwardly from the plate 33, the plates 41 being resiliently or yieldingly held to project into the space between the walls 42 and 43, by springs 44 fastened to the outside of said walls and bearing against the plates 41. The boxes, open side down, are fed from the belt 24 endwise into the space between the walls 42 and 43, being supported by the tracks 40 after they leave said belt. In order to restrain return, or reverse, movement of the boxes after they have been positioned in the carriers, yielding pawls or latches comprising angular plates 45, are pivoted, one on each lateral wall of each carrier, and are yieldingly held in a position in the path of the boxes entering the carriers by springs 46. The plates 45 retire into the recesses 47 in the walls as a box is fed thereinto, but immediately return to restrain return movement of said box, and they also assist in positioning the box in the carrier, as will be apparent. After a label has been affixed to the boxes in the carriers described, said boxes are removed from the carriers by passing them between the tracks 40 which yield to permit such passage. A part of the preferred removing mechanism for each carrier comprises a reciprocatory plunger having a head 48, adapted to be seated between the walls 42 and 43, flush with the upper surface of the carrier chamber, and yieldingly held in such position by a spring 49 interposed between the plate 33 and a flange 50 on the plunger rod 51. Each carrier is comprised in a generally radially extending portion or arm 52 of the plate 33. As the plate 33 is rotated by the Geneva movement, the carriers successively come to rest with their peripheral open ends closely adjacent the inner side of the endless belt 24, the tracks 40 being preferably slightly below the surface of the belt on which the boxes rest. In this latter position a box is fed from the belt radially of the plate 33 into the adjacent carrier, by picker mechanism having a general similarity to the picker mechanism described in the patent above referred to. This picker mechanism operates to feed a box as the several carriers come to rest, and comprises a picker finger 53 pivoted to a reciprocatory rod 54, slideable in a bearing bracket 55, fast to a stationary platform 56 within the path of the carriers. The platform 56 is supported at the top of a hollow standard 57 which extends from the lower table through the hollow shaft 30. The counter-shaft 10 is journaled in a lower slotted portion of said standard 57, and carries a cam 139

58, adapted to raise and lower an axially disposed vertical rod 59, having an anti-friction roller 60 adapted to ride on the cam 58, and a series of rack teeth 61 meshing 5 with a pinion 62 on a rock shaft 63 having an arm 64 pivoted to one end of a rod 65, the other end of the latter being pivoted to the picker rod 55. While the carriers previously referred to are at rest, the rotation of shaft 10 10 causes the finger 53 to move a box from the belt 24 into the carrier adjacent thereto, and the finger then returns to position outside the path of the boxes to be in readiness to feed a succeeding box. In order that the 15 finger 53 may pass over the boxes in its return or outward movement, it is pivoted so as to be readily deflected by the boxes, a spring 66 being employed to hold the finger in feeding position during the feeding movement.

After a box has been positioned in the carrier the latter is rotated step by step, coming to rest at different points or stations where are located the devices which 25 participate in affixing a label to the inside of the box. One or more of these stations (indicated by the letters *a* and *e*), may be utilized to inspect the boxes, no labeling operations being performed thereat. While 30 at rest at station *b*, glue is applied to the inner face or wall of the box to be labeled, in the present embodiment to the inner face of the box head. A glue pad 67 is supported opposite the open end of the boxes in the 35 carrier at station *b*, said pad comprising an upper surface 68 to which glue or other suitable adhesive may be applied and conveyed thereby to the box. In the present embodiment the pad is rectangular in shape and 40 of a size to enter the box closely adjacent the flange thereof so as to apply glue to the head closely adjacent said flange and enable a label of practically the shape and dimensions of the inner cross-section of the 45 box to be securely attached thereto. The pad 67 is fixed to the upper ends of four guide rods 69, sliding in a block 70, said pad being resiliently supported by coil springs interposed between the block and the pad. 50 The block 70 is carried at the top of a rod 71, rectangular in cross-section, and extending through the upper table, said rod 71 being vertically reciprocated through instrumentalities which will presently be described. In lower position the pad 67 is 55 spaced below the box in the carrier sufficiently to permit the upper surface of the pad to receive adhesive from a reciprocating glue transfer roller 72, which takes glue from an adhesive reservoir 73. The construction of 60 this gluing mechanism is the same as that disclosed in the prior patent referred to and need not be further described herein.

The numeral 74 indicates a label supporting piece on which are adjustably secured

upstanding guiding and retaining resilient plates 75, spaced apart in pairs, which latter and the supporting piece form a label magazine adapted to contain a pack of labels designed to be applied to the inner glued head 70 of the boxes. This magazine is disposed directly below the carrier when at station *c*, and the piece 74 is supported by an arm 76 at the upper end of a vertically reciprocating rectangular rod 77, extending through 75 the upper table, below which it is fixed to the rod 71 by a cross piece 78. Suitable extent of bearing surfaces in the upper table may be provided for the rods 77 and 71, to assist in guiding the same. A transversely disposed rock lever 79 is pivoted at one end to cross piece 78 and at its other end to a bracket 80 on the lower table, and the cross piece is elevated by a rotary cam 80 on shaft 10, the periphery of which cam 85 contacts a roller 82 on the lever 79. The plates 75 are provided with pointed fingers 83 which project upwardly and inwardly, and when a pack of labels is in position in the label magazine, the uppermost or end 90 label of the pack is pressed against said fingers, whereby the edges of the uppermost labels are slightly held from upward movement, but the uppermost label may be readily withdrawn from the magazine when the 95 pack is pressed against the glued head of the box. The label magazine is provided with a follower plate 84 from which depend four rods respectively disposed adjacent the corners of plate 84, and guided on the piece 76. 100 Two of the guide rods, 85, extend through the piece 74, and two others, 86, are of rectangular section, and have a series of fine teeth forming a ratchet 87, adapted to move past pawls 88, resiliently held in the path 105 of the ratchet by springs 89. The teeth of the ratchets are so disposed as to permit the ratchets to move in a direction to elevate the pack of labels resting on the follower 84, the follower being retained in advanced position by the pawls 88, and fine teeth are employed, as the label pack is designed to be 110 elevated in general proportion to the reduction in thickness thereof by the successive removal of the uppermost labels. In order 115 that the uppermost label of the pack may be firmly pressed against the glued head of the box, mechanism is provided to strike the follower 84 a sharp blow when the label pack is in elevated position with the uppermost 120 label practically lying against the inner face of the box head. This mechanism comprises a rod 90, loosely guided in an aperture in the piece 74, and having a head 91. The lower end of the rod 90 is in the path of a 125 resilient arm 92 fast on a rotary short shaft 93 supported from the lower table, and driven from the countershaft 10 by a sprocket and chain connection 94.

The numeral 95 indicates a fixed element 130

or bar in the path of the resilient arm 92, and disposed so that as the arm 92 rotates its outer portions contact said box 95, the arm being consequently flexed or bent by the continued rotation of the shaft 93, until its end escapes the bar 95, whereupon it sharply snaps against the rod 90 and causes the latter to deliver a hammer blow against the follower, 84, with the result that the uppermost label is firmly pressed against the glued face of the box head with sufficient force to securely adhere thereto.

As the labels are fed from the pack, in the manner above described, the plate 84 is gradually elevated so as to maintain the uppermost label substantially flush with the fingers 83. After the above operation the label magazine and the glue pad descend, and the box and adhering label move to station *d*.

Beneath the carrier at station *d* is located a presser pad 96 adapted to enter the box and press the adhering label firmly against the glued head, and smooth the label on said head, removing wrinkles, air bubbles, etc.

The pad 96 is resiliently supported and guided on a plate 97 by depending bars 98, and springs interposed between the pad and plate, and is moved into the box and against the head thereof by a lever 99 in contact with a cam 100, which latter is contoured to cause the presser pad to apply a series of separate pressures, or "pats" to the label. The cam 100 is fast on the shaft 10. At the next station, station *e*, a mirror 101 is disposed beneath the position of the carrier, at a convenient angle to reflect the interior of the box, so that the operator, if he desires, may observe whether or not the label is properly affixed. It is obvious that a mirror may be located at any other otherwise idle station, or that the idle station may be located at another point in the rotary path of the carriers, as may be desired.

It will be observed that the glue is applied to the boxes with a yielding pressure, so as not to unduly compress or possibly crush the wall of the box, and by reason of the possibility of the upper face of the pad 67 rising to and against the reacting upper face 102 of the carriers, when no box is in gluing position, means are provided to cause said glue pad to stop short of said face 102 when no box is in position to be glued. To this end a rock shaft 103 is journaled on the outside of said block, and an arm 104 on shaft 103 plays in a slot 105 in block 70, and is connected to the pad 67 by a link 106. Slidably mounted for vertical movement on block 70 is a member or stiff bent rod 107 having a forked upper end 108, and the rod 107 is provided with a pin 109 engaged by the forked end of a second arm 110 of the shaft 103. Glue pad restraining members, or detents, are mounted on the several carriers, and each detent comprises a

short non-rotatable rod 111 having a head and a depending portion 112. A spring 113 surrounds rod 111 and urges the same to dispose its head into the space of the carrier to be occupied by a box, and in the path of the incoming box, and when a box enters the carrier it moves the member 112 out of the path of the end of the rod 107, thus permitting the glue pad to rise and be pressed against the box, at which time the rod 111 is straddled by the forked end 108 of the rod 107. When there is no box in the carrier, or when it is not in correct position therein, the detent is held in the path of the rod 107, which latter upon contact therewith causes the shaft 103 to rotate in a direction to stop the rise of the pad 67 before contacting with the wall 102. The detent in the illustration is disposed to prevent the pad 67 passing the tracks 40, which operation, if the box were imperfectly positioned in the carrier, might cause it to be crushed or broken.

Labels having been applied to the inside of boxes by the foregoing construction, the labeled boxes are transferred to a second series of carriers which are adapted to hold the boxes while labels are applied to the outside, the inside labels being firmly further pressed against the heads of the boxes while the outside labeling is going on. The numeral 114 indicates a rotary support or plate, adapted to intermittently rotate synchronously with the plate 33 supporting the other or first series of carriers. On the plate 114 are secured box rests 115, preferably of rectangular shape, having flat upper faces, said rests being equal in number to the carriers on plate 33, and disposed to move in an endless circular path. Boxes, open side down, are adapted to lie one upon each box rest 115, with their lateral walls or flanges telescoping with the lateral walls of the box rests, being thus held from lateral movement relative to the rests, and their heads being firmly supported or braced by the flat upper faces of the rests.

The numeral 116 represents a vertically reciprocating pad of the size and shape of the glued surface to be given to each box, and 117 represents a label holder or magazine comprising rectangularly disposed walls between which a pack of labels may be held. The pad 116, and the label magazine 117 are disposed opposite successive points of rest in the intermittent rotary path of the rests or carriers 115, and when the boxes are at rest beneath them the pad and the magazine are moved downwardly, the former applying glue to the upper face of the head of the box on one carrier, and the latter causing the bottom label of the pack to rest upon and be pressed against the glued head of a previously glued box. Thereafter the pad and magazine move upwardly a

sufficient distance to permit the box rests to move therebeneath, and the bottom label of the pack in the magazine will adhere to the box and be withdrawn from the pack 5 upon said upward movement. The pad 116 and label magazine 117 are simultaneously moved up and down by their common supporting rod 118, square in cross-section, sliding in a bearing through table 1, and 10 operated by a cam 119 on rotary shaft 12, with which cam an anti-friction roller 120, on a long rock arm 121, engages, said rock arm being pivoted at one end on the table at 122, its opposite end being pivoted to supporting rod 118 at 123.

At different points of rest in the path of the rest 115, pressing devices 124 are provided, each comprising a presser block faced with rubber or canvas and adapted to press 20 the previously applied adhering label on the outside of the boxes and smooth the same thereon, pressing out air bubbles, etc.

Numerals 125 represent a stationary platform concentrically supported within the 25 periphery of the plate 114, and the lateral walls of the platform may serve as a bearing for the rotary plate 114, said platform being fixed to the upper table. Projecting upwardly from the platform 125, at the 30 center thereof, is a rod 126, adapted to be reciprocated by a cam 127 contacting a roller 128 on the lower end of the rod 126.

Numerals 129 indicate brackets fastened to platform 125, and at the outer ends of 35 said brackets are resiliently supported the respective presser blocks 124, these latter each comprising a stem 130 vertically sliding in bearings 131 in the brackets, and resiliently supported by springs 132 interposed between each bracket and a head 133 in each stem. Fulcrumed on each bracket 129 at 134 is a lever 135, the outer ends having an adjustable pin 136 adapted to contact the heads 133, and their inner ends being 45 in the path of contact pieces 137 on the rod 126, said contact pieces comprising projections or lugs on a sleeve 138 fastened to said rod 126. As the rod 126 rises, the levers 129 are rocked and the pressers 134 caused to contact with the labels on the 50 outside of the boxes, firmly pressing the labels on the boxes and smoothing or spreading them out thereon.

139 indicates a glue tank on table 1, and 55 three rollers are employed to transfer glue from the tank to a glue transfer roller 141, journaled in a reciprocatory frame 142, operated by a face cam 143 on shaft 12, cooperating with a rock arm 144 pivoted on 60 the lower table, and also pivoted to rod 145 pivotally joined to an arm 146 on a rock sleeve 147 journaled on a bracket 148 on the upper table, an arm 149 on said sleeve 147 being pivotally connected to said sleeve 142.

As the frame 142 is reciprocated the roller 65 141 alternately transfers glue from the last roller of the series 140 to the bottom of pad 116, when said pad is in its upper position, so that said pad will have a freshly glued 70 face to be applied to the box when it is moved down against the same. The rollers 140 are intergeared for simultaneous rotation in the usual manner, as indicated at 150, and the shaft of one roller 151 is extended and provided with a sprocket wheel 75 driven by a chain 152 from a sprocket wheel 153 on the shaft 12.

The shaft 21 is connected to intermittently rotate the plate 114 by any suitable mechanism, such as a Geneva movement explained 80 in connection with the carrier plate 33, and illustrated in Fig. 4.

After the boxes have had the labels applied, pressed and smoothed against the outside, as explained, they are stripped or ejected from the machine, preferably by being lifted from the respective rests and cast to one side. Any mechanism capable of accomplishing this result may be employed, a suitable device comprising a vertically movable rod 154, having an inwardly extending arm 155 above the path of the boxes, provided with downwardly extending spring fingers 156 terminating in shoulders or hooks 157 adapted to take beneath the inner 90 edge of each box, and lift the box until its flange edge at one side escapes the upper surface of the box rest. The movements of the arm are accomplished by a cam 158, on shaft 12, operated by a rock arm 159 pivoted to the rod 154. An ejector device comprising a finger 160 fastened to a rod 161 sliding in a bracket 162 on the platform, is operated by a rock lever 163, one arm of the latter being pivoted to the rod 161 and the 100 other arm adapted to lie in the path of the rests 115. As the rest next preceding the last pressing station moves from pressing position it rocks the lever 163 in a direction to retract the finger 160 inside of, but closely 105 adjacent to, the path of the boxes, and when the fingers 156 have lifted the box, as previously explained, the end 164 of rock lever 163 escapes the said rest 115, whereupon a spring 164' thrusts the finger 160 outwardly 110 while the box is in said elevated position, thus casting the box to one side. A spring 165, loose on the rod 161, between a collar 166 thereon, and the bracket 162, serves to cushion the ejection movement of the fingers, and to return the end 164 into the 115 path of the box rests.

It may here be stated that the supporting plate 114, box rests 115, and the gluing and labeling mechanisms associated therewith 125 to label boxes on the outside are substantially similar to the devices for performing like operations found in the patent hereto-

fore referred to. The stripping mechanism is also similar to that disclosed in the patent referred to.

The carriers of the second series are disposed to move in an endless path overlapping the path of the carriers of the first series, in the present embodiment the plate 114 being journaled to rotate in a lower horizontal plane than the plate 33, so that the box rests 115, in one position of rest, as at station *f*, are in accurate vertical alignment with the box supporting device of the first series of carriers at station *f*. When the carriers of the two series are in stationary position at station *f*, the planes of the lateral walls of the box which has had a label applied to its inner face are in parallel relation to the respective sides of the box rests 115.

20 The numeral 166 represents a rock lever fulcrumed at 167 on a bracket 168, the outer end of said lever being disposed just above the path of the upper end of the plunger rod 51, when the latter is at rest at station *f*.

25 The inner end of lever 166 is disposed above a tappet, lug, or arm 169 secured to the upper portion of the axially disposed vertically reciprocating rod 59. After the respective carriers have come to rest in overlapping position at station *f*, the upward movement of rod 59 not only causes a box to be moved from the endless belt to the adjacent carrier of the first series, but also the lug 169 depresses the outer arm of lever

30 166, which in turn depresses the plunger rod 51, and transfers the box at station *f* out of the upper carrier and causes the same to be placed in telescopic relation with the box rest immediately therebeneath, the tracks 40 being turned on their pivots to permit passage of the box, and being returned to box supporting position by the springs 44. Not only are the boxes thus transferred from one carrier series

35 40 to the other, but the upper surface of the rests 115 serve as additional means for pressing the labels on the inside of the boxes throughout their rotary path on the second series of carriers, thus avoiding a multiplicity of independent pressers for the first series which might otherwise be required. The rests 115 are of a size to nicely fit the interior of the boxes, so that the inner labels are firmly pressed against

45 50 the heads of the boxes throughout their entire area, the edges of the labels being caused to be firmly adhesively secured to the heads.

When the labels of the magazine 117 are applied to the boxes on the rests 115, the retreat of the magazine may tend to lift the boxes off their rests, should the bottom label not separate readily from the pack of labels, and to keep the boxes on the rests under such circumstances, fingers 175 are disposed

slightly above the position assumed by the upper face of the box on the rests, said fingers being fixed to brackets 176 and 177, on the platform 125 and the upper table respectively.

The operation of the machine in labeling boxes or rather hollow articles will be obvious from the above description, but a brief summary thereof may not be inadvisable at this point. The boxes to be labeled may be 70 either the cover or the container of an ordinary sectional cigarette box, and the operator places them upon the endless belt 24 open side down. The belt 24 moves the boxes into position in front of the picker 53, 80 which position is determined by a fixed cross-piece 178, beneath which the belt passes, and against which the boxes are stopped in front of the picker. When the carriers are at rest in their horizontal rotary 85 path, the picker 53 is moved transversely of the belt and the box in position at station *h* is slid from the belt into the adjacent carrier, said box moving along on tracks 40, which latter contacts the upper edge of the 90 box and serves to temporarily retain the same. The picker moves the box until its rear side escapes the pawls 45, which latter spring out and restrain the reverse movement thereof, and in this position the stop 95 112 is removed from the path of the rod 107. The picker then returns for a succeeding box, and the carrier moves a step to station *a*, where, by means of a mirror similar to the mirror 101, it may be noted whether or not 100 the box is in correct position. The carrier then makes another step, and the box comes to rest at station *b*, whereupon the glue pad 67, having previously been coated on its upper surface with glue or other suitable adhesive, rises, and its glued face is pressed against the head of the box on the inside thereof. The glue pad then retreats to its lowermost position, and the carrier makes another step, the box arriving at station *c*, 110 beneath which is located the label magazine comprising fingers 75. This magazine then rises and the top label of the pack in the magazine is pressed against the glue head of the box, the "snapper" 92 giving a strong 115 pressure for an instant in order to cause the label to more surely adhere to the box. Said label magazine having retreated the carrier is moved another step to station *d*, where the presser 96 is raised into the box and the 120 adhering label is firmly pressed against the box, the cam 101 having a plurality of elevated portions so as to cause the presser 96 to, as it were, "pat" the label against the box several times while at this station. The 125 presser 96 having retreated to its lowermost position, the carrier moves to station *e*, at which, by looking in the mirror 101 the label on the inside of the box may be observed. The carrier then moves to station *f*, and, it 130

will be clear from the foregoing, that the other series of carriers on the plate 114 have moved synchronously with the series of carriers just referred to, and hence one of the 5 box rests 115 of the second series of carriers will be in box-receiving position beneath the upper carrier at station *f*. Both carriers being at rest at station *f*, the rod 59 rises, and the arm 169 rocks the lever 166, which latter 10 depresses the rod 51, causing the head 48 thereof to force the box from the upper onto the lower carrier through the plane of the upper carrier, the path of the box, when being transferred, thus intersecting that of the 15 upper carrier, the box assuming a telescopic position on the lower carrier and being firmly pressed thereagainst by the head 48. The rod 59 then moves downwardly and the head 48 returns to its seat, whereupon the 20 box, now on the second carrier, is moved intermittently to the gluing, labeling, and pressing devices previously described, and by means of which a label is applied and adhesively affixed to the outside of the head of 25 the labeled box in a position opposite to the label previously applied. While this invention is herein disclosed as embodied in a machine which applies labels to boxes, and similar articles, it is of course to be understood 30 that strips of material similar to label material in their texture or mode of application are within the purview of the invention; the invention finding ready applicability whether the strips to be applied are or 35 are not printed or otherwise marked. It will be noted that each operation in affixing a label to the outside of the box in the manner previously described causes the label on the inside to be further pressed against the 40 inside of the box, so that if by any possibility it should not have adhered to the inside at all points its adherence is practically assured by the subsequent pressing operations just mentioned. The outside label having 45 been applied and pressed on the box, the box is lifted from the box rests and thrown to one side into a convenient receptacle.

It will be noted that in the embodiment disclosed herein, the carriers are comprised 50 in horizontally rotating elements, and that the plane of feed of the boxes from the belt to the carrier which directly receives it is substantially parallel to the plane of the path of said carrier. This disposition of 55 the parts makes for simplicity, both in construction and operation, it not being required to positively hold the boxes on the belt, or when being transferred to the first carrier, and but one movement being required 60 to transfer an inside-labeled box to the second carrier, this movement being preferably at an angle to the plane of the first carrier. Thus by the above construction are accomplished, among others, the objects hereinbefore stated.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense. 70

Having described my invention, what I 75 claim as new and desire to secure by Letters Patent is:

1. In an apparatus of the character described, in combination, a plurality of box carriers adapted to move in endless overlapping paths, and mechanism adapted to affix a label to a box on one carrier, transfer said labeled box to another of said carriers in a path intersecting each of said endless paths, and affix another label to said 80 labeled box on said other carrier. 85

2. In an apparatus of the character described, in combination, a plurality of box carriers adapted to move in endless overlapping paths, mechanism adapted to affix 90 a label to a box on one carrier, and means adapted to move said labeled box to another carrier in a path within the overlapping portions of said two carriers.

3. In an apparatus of the character described, in combination, a plurality of box carriers adapted to move in endless overlapping paths, mechanism adapted to affix a label to an inside face of a box on one carrier, means adapted to transfer said 95 labeled box to another of said carriers, and means adapted to affix another label to an outside face of said labeled box on said other carrier. 100

4. In an apparatus of the character described, in combination, a plurality of box carriers adapted to move in endless overlapping paths, mechanism adapted to feed boxes successively to one of said carriers, mechanism adapted to affix labels to the inside faces of the boxes on one carrier, successively transfer said labeled boxes to another of said carriers, and affix other labels to the outside faces of the labeled boxes on said other carrier, and devices associated with said respective carriers adapted to press said boxes and applied labels against each other. 105 110 115

5. In an apparatus of the character described, in combination, a plurality of carriers adapted to move boxes in endless overlapping paths, one of said carriers comprising means adapted to support boxes so as to expose the interior thereof, and mechanism adapted to affix a label to an inner face of a box on said supporting means, transfer said labeled box to another of said carriers, and affix another label to said labeled box on said other carrier. 120 125

6. In an apparatus of the character de- 130

scribed, in combination, a plurality of box carriers adapted to move in endless overlapping paths, one of said carriers comprising pairs of spaced fingers, adapted to support boxes so as to expose the interior thereof, means adapted to resiliently hold said fingers in supporting position, a box remover opposite each pair of fingers, mechanism adapted to affix labels to the inner faces of boxes on said supporting means, means adapted to successively operate said remover to transfer said labeled boxes to another of said carriers, and means adapted to affix other labels to said labeled boxes on said other carrier.

7. In an apparatus of the character described, in combination, a plurality of box carriers adapted to move in endless overlapping paths, one of said carriers comprising pairs of spaced fingers adapted to support boxes so as to expose the interior thereof, means adapted to resiliently hold said fingers in supporting position, a box remover opposite each pair of fingers, means adapted to feed boxes into supported position on said fingers, means adapted to restrain reverse movement of said boxes when in supported position on said fingers, mechanism adapted to affix labels to the inner faces of boxes on said supporting means, means adapted to successively operate said removers to transfer said labeled boxes past said fingers to another of said carriers, and means adapted to affix other labels to said labeled boxes on said other carrier.

8. In an apparatus of the character described, in combination, a plurality of box carriers adapted to move in endless overlapping paths, one of said carriers comprising means adapted to support boxes so as to expose the interior thereof, a glue pad, means adapted to move said pad into successive boxes on said supporting means and thereby apply glue to the inner face of said boxes, and mechanism adapted to apply labels to the glued faces of the boxes on said carrier, transfer said labeled boxes to another of said carriers and affix other labels to the outside faces of said labeled boxes on said other carrier.

9. In an apparatus of the character described, in combination, a plurality of box carriers adapted to move in endless overlapping paths, one of said carriers comprising means adapted to support boxes so as to expose the interior thereof, a glue pad, means adapted to move said pad into successive boxes on said supporting means and thereby apply glue to the inner faces of said boxes, mechanism adapted to apply labels to the glued faces of the boxes on said carrier, transfer said labeled boxes to another of said carriers and affix other labels to the outside faces of said labeled boxes on said

other carrier, and devices adapted to cause the movement of said pad toward the carrier to stop short of the carrier when no box is in glue applying position thereon.

10. In an apparatus of the character described, in combination, a plurality of box carriers adapted to move in endless overlapping paths, one of said carriers comprising a plurality of means adapted to support boxes so as to expose the interior thereof, means adapted to feed boxes to said supporting means, pad restraining members adapted to be displaced by said boxes when in position on said supporting means, a glue pad, means adapted to move said pad into successive boxes on said supporting means and thereby apply glue to the inner faces of said boxes, and mechanism adapted to apply labels to the glued faces of the boxes on said carrier, transfer said labeled boxes to another of said carriers and affix other labels to the outside faces of said labeled boxes on said other carrier, said pad comprising a member adapted to contact with said restraining member when no box is in glue applying position on said supporting means.

11. In an apparatus of the character described, in combination, a plurality of box carriers adapted to move in endless overlapping paths, pairs of box supporting tracks mounted on one of said carriers, means adapted to feed boxes along said tracks into predetermined position such that the interior thereof is exposed, yieldingly mounted glue pad restraining members adapted to be displaced by said boxes when in said predetermined position, means adapted to restrain reverse movement of said boxes on said tracks, a yieldingly mounted glue pad comprising a member in alignment with said restraining member when no box is in glue applying position on said tracks, means adapted to move said pad into respective boxes on said tracks to apply glue to inner faces thereof, and mechanism adapted to apply labels to the glued faces of said boxes, transfer said labeled boxes to another of said carriers, and affix other labels to the outside faces of said labeled boxes on said other carrier.

12. In an apparatus of the character described, in combination, a plurality of box carriers adapted to move in endless overlapping paths, one carrier comprising means adapted to support boxes and expose the interior thereof, and another carrier comprising means adapted to support boxes and expose the exterior thereof, means adapted to move said carriers so that the box supporting means of one align with those of the other in pairs, and means adapted to affix labels to the faces of the boxes on the supporting means of one carrier, transfer the

labeled boxes to the supporting means of the other carrier when in alinement, and affix other labels to the faces of the labeled boxes opposite said labeled face.

5 13. In an apparatus of the character described, in combination, a plurality of box carriers adapted to move in endless overlapping paths, one carrier comprising means adapted to support boxes and expose the interior thereof, and another carrier comprising means adapted to support boxes and expose the exterior thereof, means adapted to move said carriers so that the box supporting means of one aline with those of the other in pairs, means adapted to affix labels to the interior faces of the boxes on the supporting means of one carrier, means adapted to press said labeled boxes onto the supporting means of said other carrier, and means adapted to affix labels to the exterior faces of said boxes when on said other carrier.

25 14. In an apparatus of the character described, in combination, a plurality of box carriers adapted to move in endless overlapping paths, one carrier comprising means adapted to support boxes and expose the interior thereof, and another carrier comprising means adapted to support boxes and expose the exterior thereof, means adapted to move said carriers so that the box supporting means of one aline with those of the other in pairs, means adapted to affix labels to the interior faces of the boxes on the supporting means of one carrier, means adapted to transfer said labeled boxes to the supporting means of the other carrier and press their labeled faces thereagainst, and means adapted to affix labels to the exterior faces of said boxes opposite said labeled face when on said other carrier.

35 15. In an apparatus of the character described, in combination, a plurality of rotary carriers adapted to move in overlapping paths, one of said carriers comprising a plurality of pairs of spaced yielding tracks, and the other carrier comprising a plurality of rests, means adapted to intermittently rotate said carriers and cause said tracks and rests to aline in pairs, means adapted to feed boxes along said pairs of tracks into predetermined position thereon so that the interior of said boxes is disposed toward the plane of said rests, means adapted to affix labels to the inner faces of the boxes on said tracks, means adapted to push said labeled boxes transversely of said tracks and cause the same to telescope with said rests when in alinement, and means adapted to affix labels to the exterior of said labeled boxes on said rests.

45 16. In an apparatus of the character described, in combination, a plurality of rotary carriers adapted to move in overlapping paths, one of said carriers comprising a plu-

rality of pairs of spaced yielding tracks, and the other carrier comprising a plurality of rests, means adapted to intermittently rotate said carriers and cause said tracks and rests to aline in pairs, means adapted to feed boxes 70 along said pairs of tracks into predetermined position thereon so that the interior of said boxes is disposed toward the plane of said rests, means adapted to affix labels to the inner faces of the boxes on said tracks, means adapted to push said labeled boxes transversely of said tracks and cause the same to telescope with and the labeled faces to be pressed against said rests when in alinement, and means adapted to affix 80 labels to the exterior of said labeled boxes on said rests.

17. In an apparatus of the character described, in combination, a plurality of carriers adapted to move in endless overlapping paths, means adapted to feed boxes to one carrier in a plane substantially parallel to the plane of the path of said carrier, means adapted to transfer boxes from said latter carrier to the other carrier, and means 90 adapted to affix labels to the inner faces of the boxes on one carrier and the outer faces of the boxes on the other carrier.

18. In an apparatus of the character described, in combination, a plurality of carriers adapted to move in endless overlapping paths, means adapted to feed boxes to one carrier in a plane substantially parallel to the plane of the path of said carrier, means adapted to transfer boxes from said 100 latter carrier to the other carrier, in a path at an angle to the plane of said latter path, and means adapted to affix labels to the inner faces of the boxes on one carrier and the outer faces of the boxes on the other carrier. 105

19. In an apparatus of the character described, in combination, a plurality of carriers adapted to move in endless overlapping paths, means adapted to feed boxes to one carrier in a plane substantially parallel to the plane of the path of said carrier, means adapted to transfer boxes from said latter carrier to the other carrier in a path perpendicular to the path of said carrier, 110 and means adapted to affix labels to the inner faces of the boxes on one carrier and the outer faces of the boxes on the other carrier. 115

20. In an apparatus of the character described, in combination, a plurality of carriers adapted to move in endless overlapping paths, said carriers each comprising a series of box supporting and positioning devices, means adapted to intermittently move said carriers so that the supporting and positioning devices of one carrier aline with those of the other when said carriers are at rest, means adapted to affix labels to the inner faces of boxes on one carrier and 120 125 130

to the outer faces of boxes on the other carrier, and means adapted to transfer boxes from one carrier to the other.

21. In an apparatus of the character described, in combination, a plurality of carriers adapted to move in endless overlapping paths, said carriers each comprising a series of box supporting and positioning devices, means adapted to intermittently move said carriers so that the supporting and positioning devices of one carrier aline with those of the other when said carriers are at rest, means adapted to affix labels to the inner faces of boxes on one carrier and

10 to the outer faces of boxes on the other carrier, and means adapted to transfer boxes from one carrier to the other, comprising a box moving plunger adapted to be disposed opposite said alining point of said supporting and positioning devices.

15 22. In an apparatus of the character described, in combination, a plurality of carriers adapted to move in endless overlapping paths, said carriers each comprising a series of box supporting and positioning devices, means adapted to intermittently move said carriers so that the supporting and positioning devices of one carrier aline with those of the other when said carriers are at rest, means adapted to affix labels to the inner faces of boxes on one carrier and

20 to the outer faces of boxes on the other carrier, and means adapted to transfer boxes from one carrier to the other comprising a box moving plunger adapted to be disposed opposite said alining point of said supporting and positioning devices.

25 22. In an apparatus of the character described, in combination, a plurality of carriers adapted to move in endless overlapping paths, said carriers each comprising a series of box supporting and positioning devices, means adapted to intermittently move said carriers so that the supporting and positioning devices of one carrier aline with those of the other when said carriers are at rest, means adapted to affix labels to the inner faces of boxes on one carrier and

30 to the outer faces of boxes on the other carrier, and means adapted to transfer boxes from one carrier to the other, comprising a box moving plunger adapted to be disposed opposite said alining point of said supporting and positioning devices, and means adapted to cause said plunger to move the inside labeled box from one carrier to the other and press its labeled face against the latter.

35 23. In an apparatus of the character described, in combination, a plurality of carriers adapted to move in endless overlapping paths, said carriers each comprising a series of box supporting and positioning devices, means adapted to intermittently move said carriers so that the supporting and positioning devices of one carrier aline with those of the other when said carriers are at rest, means adapted to affix labels to the inner faces of boxes on one carrier and

40 to the outer faces of boxes on the other carrier, and means adapted to transfer boxes from one carrier to the other, comprising a box moving plunger adapted to be disposed opposite said alining point of said supporting and positioning devices, and means adapted to cause said plunger to move the inside labeled box from one carrier to the other and press its labeled face against the latter.

45 23. In an apparatus of the character described, in combination, a plurality of carriers adapted to move in endless overlapping paths, said carriers each comprising a series of box supporting and positioning devices, means adapted to intermittently move said carriers so that the supporting and positioning devices of one carrier aline with those of the other when said carriers are at rest, means adapted to affix labels to the inner faces of boxes on one carrier and

50 to the outer faces of boxes on the other carrier, and means adapted to transfer boxes from one carrier to the other, comprising a box moving plunger adapted to be disposed opposite said alining point of said supporting and positioning devices, and means adapted to cause said plunger to move the inside labeled box from one carrier to the other and press its labeled face against the latter, comprising a rock lever having an arm spaced from and adapted to move into contact with said plunger.

55 24. In an apparatus of the character described, in combination, a plurality of carriers adapted to move in endless overlapping paths, said carriers each comprising a series of box supporting and positioning devices, means adapted to intermittently move said carriers so that the supporting and positioning devices of one carrier aline with those of the other when said carriers are at rest, means adapted to affix labels to the inner faces of boxes on one carrier and

60 to the outer faces of boxes on the other carrier, and means adapted to transfer boxes from one carrier to the other comprising plungers on one carrier opposite the respective supporting and positioning means.

75 25. In an apparatus of the character described, in combination, a plurality of carriers adapted to move in endless overlapping paths, said carriers each comprising a series of box supporting and positioning devices, means adapted to intermittently move said carriers so that the supporting and positioning devices of one carrier aline with those of the other when said carriers are at rest, means adapted to affix labels to the inner faces of boxes on one carrier and

75 to the outer faces of boxes on the other carrier, and means adapted to transfer boxes from one carrier to the other comprising plungers on one carrier opposite the respective supporting and positioning means.

80 25. In an apparatus of the character described, in combination, a plurality of carriers adapted to move in endless overlapping paths, said carriers each comprising a series of box supporting and positioning devices, means adapted to intermittently move said carriers so that the supporting and positioning devices of one carrier aline with those of the other when said carriers are at rest, means adapted to affix labels to the inner faces of boxes on one carrier and

85 to the outer faces of boxes on the other carrier, and means adapted to transfer boxes from one carrier to the other comprising plungers on one carrier opposite the respective supporting and positioning means, and a rock lever having an arm disposed opposite said plungers at the alining point of the supporting and positioning devices of said carriers.

90 26. In an apparatus of the character described, in combination, a pair of carriers, one of said carriers comprising means adapted to retain a hollow article by contact with the outer surface thereof, and the other carrier comprising means adapted to retain a hollow article by contact with an interior surface thereof, means adapted to move said carriers in adjacent paths, and means adapted to transfer a hollow article from the retaining means of one of said carriers to that of said other carrier.

95 27. In an apparatus of the character described, in combination, a pair of carriers, one of said carriers comprising yielding means adapted to contact the edge of a hollow article and retain the same thereon, and the other carrier comprising means adapted to retain a hollow article by contact with an interior surface thereof, means adapted to move said carriers in adjacent paths, and means adapted to move a hollow article from the retaining means of one carrier to that of the other in a direction to cause said edge contacting means to yield and permit the article to pass.

100 27. In an apparatus of the character described, in combination, a pair of carriers, one of said carriers comprising yielding means adapted to contact the edge of a hollow article and retain the same thereon, and the other carrier comprising means adapted to retain a hollow article by contact with an interior surface thereof, means adapted to move said carriers in adjacent paths, and means adapted to move a hollow article from the retaining means of one carrier to that of the other in a direction to cause said edge contacting means to yield and permit the article to pass.

105 28. In an apparatus of the character described, in combination, a pair of carriers, one of said carriers comprising means adapted to retain a hollow article by contact with the outer surface thereof, and the

- other carrier comprising means adapted to retain a hollow article by contact with an interior surface thereof, means adapted to move said carriers in adjacent paths, and means adapted to transfer a hollow article from the retaining means of one of said carriers to that of said other carrier through the plane of the former carrier.
29. In an apparatus of the character described, in combination, a pair of carriers, one of said carriers comprising means adapted to retain a hollow article by contact with the outer surface thereof, and the other carrier comprising means adapted to retain a hollow article by contact with an interior surface thereof, means adapted to intermittently move said carriers in paths which overlap at a stationary point in said paths, and means adapted to transfer a hollow article from the retaining means of one carrier to that of the other.
30. In an apparatus of the character described, in combination, a pair of carriers, one of said carriers comprising means adapted to retain a hollow article by contact with the outer surface thereof, and the other carrier comprising means adapted to retain a hollow article by contact with an interior surface thereof, means adapted to intermittently move said carriers in paths which overlap at a stationary point in said paths, and means adapted to transfer a hollow article from the retaining means of one carrier to that of the other through the plane of the former carrier.
31. In an apparatus of the character described, in combination, a pair of carriers, one of said carriers comprising means adapted to retain a hollow article by contact with the outer surface thereof, and the other carrier comprising means adapted to retain a hollow article by contact with an interior surface thereof, means adapted to move said carriers in adjacent paths, means adapted to transfer a hollow article from the retaining means of one of said carriers to that of said other carrier, and means adapted to affix a label to said article while on one of said carriers.
32. In an apparatus of the character described, in combination, a pair of carriers, one of said carriers comprising means adapted to retain a hollow article by contact with the outer surface thereof, and the other carrier comprising means adapted to retain a hollow article by contact with the interior surface thereof, means adapted to move said carriers in adjacent paths, means adapted to transfer a hollow article from the retaining means of one of said carriers to that of said other carrier, and means adapted to affix a label to the interior of the article retained by its exterior surface, and to the exterior of the article retained by its interior surface.
33. In an apparatus of the character de-
- scribed, in combination, a pair of carriers, one of said carriers comprising means adapted to retain a hollow article by contact with the outer surface thereof, and the other carrier comprising means adapted to retain a hollow article by contact with an interior surface thereof, means adapted to intermittently move said carriers in paths which overlap at a stationary point in said paths, means adapted to transfer a hollow article from the retaining means of one carrier to that of the other through the plane of the former carrier, and means adapted to affix a label to the interior of the article retained by its exterior surface, and to the exterior of the article retained by its interior surface.
34. In an apparatus of the character described, in combination, a plurality of article carriers adapted to move in endless overlapping paths, mechanism adapted to perform a labeling operation on an article on one carrier, means adapted to move said labeled article to another carrier in a path within the overlapping portions of said two carriers, and means adapted to perform a labeling operation on said article while on said latter carrier.
35. In an apparatus of the character described, in combination, a pair of carriers, means adapted to move said carriers in predetermined paths, means adapted to feed an article to one of said carriers, means adapted to apply a label to said article while on said carrier, means adapted to move said labeled article through the plane of said carrier to said other carrier, and means adapted to affix another label to said box while on said other carrier.
36. In an apparatus of the character described, in combination, a pair of carriers adapted to move in endless overlapping paths, means adapted to feed an article to one of said carriers, means adapted to apply a label to said article while on said carrier, means adapted to move said labeled article therefrom to said other carrier in a path intersecting said former carrier, and means adapted to apply a label to said article while on said other carrier.
37. In an apparatus of the character described, in combination, a pair of carriers, means adapted to move said carriers in predetermined overlapping paths, means adapted to feed an article to one of said carriers, means adapted to apply a label to said article while on said carrier, means adapted to move said labeled article through the plane of said carrier to said other carrier, and means adapted to perform a labeling operation on said article while on said other carrier.
38. In an apparatus of the character described, in combination, a support, means adapted to adhesively affix a label to an inner wall of a box, means adapted to apply

said labeled box to said support so as to support said labeled wall, and means adapted to adhesively affix another label to the outside face of said labeled wall while the 5 box is on said support.

39. In an apparatus of the character described, in combination, a support, means adapted to adhesively affix a label to an inner wall of a box, means adapted to apply 10 said labeled box to said support so as to support said labeled wall, and means adapted to adhesively affix another label to the outside face of said box opposite said

labeled wall while the box is on said support. 15

40. In an apparatus of the character described, in combination, box carrying means, and mechanism adapted to coöperate therewith to affix labels to the inner and the outer faces of a box while on said carrying means. 20

In testimony whereof I affix my signature, in the presence of two witnesses.
